UNITED STATES PATENT OFFICE

JOSEPH F. MORAN, OF WATERBURY, CONNECTICUT, ASSIGNOR TO SCOVILL MANUFACTURING COMPANY, OF WATERBURY, CONNECTICUT

DESIGN FOR A SPRINKLER HEAD

Application filed December 23, 1930. Serial No. 38,098. Term of patent 7 years.

To all whom it may concern:

Be it known that I, JOSEPH F. MORAN, a citizen of the United States, residing at Waterbury, in the county of New Haven, State of Connecticut, have invented a new, original, and ornamental Design for a Sprinkler Head, described and represented in the following specification and the accompanying drawings, forming a part of the same, in which,—

I claim:

The ornamental design for a sprinkler head as shown.

JOSEPH F. MORAN.
